Earle C. Bullock and David D. Hunting, East Grand Rapids, Mich., assignors to Steelcase Inc., Grand Rapids, Mich., a corporation of Michigan

Application July 28, 1954, Serial No. 31,638

Term of patent 14 years

(Cl. D74—9)

FIG. 1

FIG. 3

Fig. 1 is a side perspective view of a letter tray showing our new design, the side opposite thereto presenting a similar appearance;

Fig. 2 is a sectional view thereof taken along the plan II—II of Fig. 1; and

Fig. 3 is a fragmentary top plan view thereof.

The dominant features of our design reside in the portion shown in full lines.

We claim:

The ornamental design for a letter tray, substantially as shown and described.
